UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

LUNCH-BOX.

1,058,068.

Specification of Letters Patent.

Patented Apr. 8, 1913.

Application filed March 5, 1912. Serial No. 881,683.

To all whom it may concern:

Be it known that I, JOSEPH F. LAMB, a citizen of the United States, and a resident of New Britain, in the county of Hartford, 5 State of Connecticut, have invented certain new and useful Improvements in Lunch-Boxes, of which the following is a specification.

The object of the invention is to produce 10 a device of the character described having features of novelty and advantage.

An embodiment of the invention is illustrated in the drawings in which—

Figure 1 is a side elevation with parts 15 broken away to show construction. Fig. 2 is a sectional end view.

a denotes the base or food compartment having slide ways *b* at the upper side edges thereof, *c* denotes the top, the lower side 20 edges of which are channeled as at *d*, to fit about said slideways and to provide a sliding engagement between said top and bottom.

e is a bottle holder secured within the top 25 which may be of any form, such as a pair of spring clips as illustrated, or some other equivalent device.

At one end of the base there is provided 30 a spring supported pin *f* adapted to interlock with the rolled over edge *g* of one end of the top, the lower edge of the other end of the top being extended downwardly as at *i* to form a stop.

In Fig. 1 the parts are shown in assembled position. The movement of the top 35 to the left will cause the pin to be depressed unlocking the top which can then be slid off of the base exposing the food compartment below and the bottle carried in a suitable holder in the top. To assemble the parts, 40 the channels at the edges of the top are fitted onto the slideways and then the top is slid onto the base until the edge *g* passes over the spring pin *f*, the depending edge *i* of the opposite end of the box coming up against 45 the base to form a stop.

I claim as my invention:

In a lunch box a base having side walls, slideways formed at the upper side edges thereof, a top having side walls, channels 50 formed at the lower side edges thereof adapted to engage said slideways, a closure for each end of said top, a spring supported pin mounted in said base and adapted to engage the lower edge of one of the closures of 55 said top, and a depending flange on the opposite closure adapted to bear against the opposite end of said base to form a positioning stop.

JOSEPH F. LAMB.
